(57) **CLAIM**

The ornamental design for a display screen or portion thereof with graphical user interface, as shown and described.

DESCRIPTION

FIG. 1 is a front view of a display screen or portion thereof with graphical user interface showing a first embodiment of the new design;

FIG. 2 is a front view of a display screen or portion thereof with graphical user interface showing a second embodiment of the new design;

FIG. 3 is a front view of a display screen or portion thereof with graphical user interface showing a third embodiment of the new design;

FIG. 4 is a front view of a display screen or portion thereof with graphical user interface showing a fourth embodiment of the new design; and,

FIG. 5 is a front view of a display screen or portion thereof with graphical user interface showing a fifth embodiment of the new design.

The broken line showing of texts, numerals, and graphic elements forms no part of the claimed design.

The outmost dot-dashed lines in the figures show a display screen or portion thereof, and form no part of the claimed design.

1 Claim, 5 Drawing Sheets
